CLAIM

I claim the ornamental design for a toilet stool foot rest, as shown and described.

DESCRIPTION

FIG. 1 is a perspective view of a toilet stool foot rest; FIG. 2 is a left side elevation view thereof; FIG. 3 is a right side elevation view thereof; FIG. 4 is a front side elevation view thereof; FIG. 5 is a rear side elevation view thereof; FIG. 6 is a top plan view thereof; and, FIG. 7 is a bottom plan view thereof.
The uniformly broken lines in the drawings depict portions of the toilet stool foot rest that form no part of the claimed design.
